C. LIPPER

TEXTILE MOUNTED CAMPHOR BALL

Filed Sept. 24, 1926

INVENTOR:

CLARENCE LIPPER,

BY *Niederhoffer & Goldsmith*.

ATTORNEYS.

UNITED STATES PATENT OFFICE.

CLARENCE LIPPER, OF PHILADELPHIA, PENNSYLVANIA, ASSIGNOR TO LIPPER MANUFACTURING CO. INC., OF PHILADELPHIA, PENNSYLVANIA, A CORPORATION OF PENNSYLVANIA.

TEXTILE-MOUNTED CAMPHOR BALL.

Application filed September 24, 1926. Serial No. 137,403.

My invention relates to new and useful textile mounted camphor balls and it relates more particularly to camphor balls which are permanently encased in an open mesh 5 tubular textile covering, in a flexible and pliable string formation, ready for any general use and particularly adapted to be suspended in closets, chests or the like.

In the application and the handling of 10 camphor balls, as an insecticide, chiefly against moths and the like, great difficulty and inconvenience have been experienced, in placing and maintaining the camphor balls in close proximity to the clothing or 15 other material to be protected and a great deal of time and effort is consumed in distributing the innumerable individual camphor balls when storing away clothing and in gathering the same again when unpack- 20 ing.

With a view of overcoming the above difficulties, in an expeditious manner, and at a minimum cost, my invention contemplates a 25 article of manufacture comprising a series, or a string of camphor balls, or the like, permanently encased within a continuous open mesh tubular textile covering or casing, each ball being encased therein individually and separated from the next succeeding camphor ball by a short constriction 30 of the outer tubular textile casing, whereby the camphor balls are maintained in suitable string formation of any desired and suitable length, and in such form may be positioned 35 conveniently at any desired point in a closet, chest, trunk or the like, in which clothing is stored.

My invention further contemplates a 40 string of textile mounted camphor balls, whereby said camphor balls may readily be suspended at any place, quickly and without handling an innumerable number of individual camphor balls. Thus, moreover, the camphor balls may be handled more readily 45 both in their application to a closet, chest, trunk or the like, that is, in their distribution within a closet, as well as in the handling of the same when it is desired to remove the camphor balls from the closet, in 50 unpacking or removing the clothing from the same.

Thus after a trunk or chest has been packed and stored over a period of time with

camphor balls distributed throughout the 55 contents thereof, it will not be necessary, according to my invention, to gather up innumerable individual camphor balls, some broken, crumpled and crushed, but simply to remove several strings of camphor balls 60 which are permanently and conveniently encased in an open mesh textile mounting, whereby such strings may moreover, be 65 stored away for future use and may be used over and over again, without any appreciable loss of the camphor balls due to breakage.

With the above ends in view, my invention 70 consists of a suitable open mesh, seamless tubular braided textile mounting, having positioned therein at spaced intervals, individual camphor balls; the open mesh 75 braided or knitted tubular casing being constricted intermediate each two successive camphor balls, so as to maintain said balls in fixed and spaced relation to each other and thus to prevent the abrasion of the camphor balls by contact with each other, said casing being also permanently closed at both 80 ends and being preferably provided with a suitable loop or the like at one end thereof, whereby the same may be conveniently suspended at any point, if so desired.

For the purpose of illustrating my invention, I have shown in the accompanying drawings, a form thereof, which is at present preferred by me since it will give in 85 practice, satisfactory and reliable results, although it is to be understood that the various instrumentalities of which my invention consists can be variously arranged and organized and that my invention is not 90 limited to the precise arrangement and organization of these instrumentalities as herein shown and described.

In the accompanying drawings, Figure 1 represents a perspective view of 95 a string of textile mounted camphor balls embodying my invention.

Figure 2 represents a front elevation of a fragmentary portion of the string of camphor balls, shown on a greatly enlarged 100 scale, illustrating the detail construction thereof.

Referring to the drawings, in which like reference characters indicate like parts, 1 designates a seamless tubular textile camphor ball mounting embodying my inven- 105

tion, comprising a series of camphor balls or globules 2, or the like, surrounded by a continuous outer tubular casing 3 of an open mesh textile material which is formed with a generally open texture at the centers of the balls or globules 2, as shown in Figures 1 and 2, and which, moreover, is formed with closely drawn, constricted portions 4, intermediate each two successive balls.

10 In the particular illustration of my invention, shown in the drawings, the outer textile casing 3 is a seamless braided tube, though it is to be understood that a knitted outer tubular textile formation may be also employed for this purpose.

In the formation of the textile mounted camphor balls, according to my invention, as illustrated in the drawings, a suitable seamless tube, of any desired textile thread 20 or the like, is braided with alternate, open meshed and dense portion, at suitable intervals, a camphor ball or globule 2 being inserted into the tube at said intervals and the formation of the tube continued about 25 said camphor ball or globule, constricting the tubular formation between each two successive balls, thereby to maintain said camphor balls in constant fixed and spaced relation to each other.

30 The end 5 of the braided tubing 3 is permanently closed by any suitable means, such as stitching, or the like, as shown in Figure 1, while the upper terminal of the string of textile mounted or encased camphor balls is 35 provided with a braided end 6, which is a continuation of the tubular braided casing of the mounting, which is then turned back upon itself at 7, as shown in Figure 1, so as to form a loop 8; the free end 9 of the braiding being sewed or otherwise secured to the portion 6, at the point 10, so as to form a permanent loop at the same time permanently closing the upper end of the tubular textile mounting. By this means a permanent 45 structure is formed, closed at both ends, and having the camphor balls positioned in close relation to each other and surrounded in main, by an open mesh casing, so as to expose the same to the atmosphere to the 50 largest degree. The constricted portions 4, intermediate the successive camphor balls, prevent the displacement of the latter and any frictional contact between the same.

55 It will thus be seen, that by my novel invention, not only the handling, but also the application and use of camphor balls, and the like, is greatly facilitated, since it is not necessary to handle innumerable camphor balls, and to place and distribute the same 60 individually throughout the closet, trunk or chest, the contents of which are to be protected, but merely a few strings of permanent textile mounted camphor balls, as shown in Figure 1, are positioned at suitable 65 points throughout the closet, thereby per-

meating the atmosphere of the closet with the vapors of the camphor balls to a maximum degree. Similarly, the removal of the camphor balls will be greatly facilitated, since it is only necessary to remove comparatively few strings of camphor balls rather than a multitude of individual camphor balls.

70 While in the foregoing description reference is made merely to camphor balls or globules, it is to be understood that my invention is applicable to textile mounted globules or balls of camphor or other suitable volatile insecticidal materials, which depend upon the volatile vapors thereof for 75 their insecticidal action, said vapors permeating the atmosphere, as in the case of the volatile vapors of camphor.

80 Similarly, while in the particular illustration shown and described, reference is 85 made only to substantially balls or spherical shaped globules of camphor or the like, such shape may be varied, as for instance, cubical or polyhedral globules may be employed. The essence of my invention will therefore 90 be seen to reside in the mounting of a series of globules, balls or lumps of a volatile insecticidal solid, in an open mesh seamless tubular textile outer casing, within which 95 said globules or balls are positioned in spaced relation to each other, and well exposed to the atmosphere, thereby to afford convenient means of handling such globules or balls of the volatile solids, both in dispensing or merchandising the same, and 100 particularly however, in the application of the same to closets, trunks, or chests. By 105 this means, moreover, the greatest effect of the volatile vapors of the solid may be had, without the camphor or other material coming in contact with the clothing.

110 It will now be apparent that I have devised new and useful textile mounted camphor balls, which embodies the features of advantage enumerated as desirable in the statement of the invention and the above description and while I have in the present instance shown and described a preferred embodiment thereof which will give in practice, satisfactory and reliable results, it is 115 to be understood that such embodiment is susceptible of modification in various particulars without departing from the spirit or scope of the invention or sacrificing any 120 of its advantages.

125 While in the foregoing description of my invention reference has been made specifically only to a braided tubular casing, it is to be understood however, that my invention is not limited to a braided tubing, but my invention may be carried out by any other textile operation resulting in a tubular casing embodying the novel features and functions of my invention. Thus any tubular textile casing may be employed to produce 130

the novel article of manufacture of my invention, as may fall within the scope of the claims forming part of this specification.

Having thus described my invention, 5 what I claim as new and desire to secure by Letters Patent is:—

1. In a device of the character stated an elongated tubular textile casing and a series of camphor globules permanently encased 10 therein and maintained in spaced relation to each other, portions of said tubular textile casing intermediate of said globules being constricted by the texture thereof, while the portions of said textile casing immediately 15 surrounding said globules conform to the contour of said globules.

2. In a device of the character stated an elongated tubular textile casing, a series of camphor globules permanently encased 20 therein and maintained in spaced relation to each other, portions of said tubular textile casing intermediate of said globules being constricted by the texture thereof, while the portions of said textile casing immediate- 25 ly surrounding said globules conform to the contour of said globules, and a suspension loop at the terminal of said textile casing.

3. In a device of the character stated an elongated seamless tubular textile casing, a 30 series of camphor globules permanently enclosed within said tubular textile casing and maintained therein in spaced relation to each other by the texture of the tubular casing, and a suspension loop at the terminal of 35 said textile casing formed of, and integrally

with, said textile casing by folding back the terminal portion thereof and securing the end to the casing.

4. In a device of the character stated, an elongated tubular textile casing, a series of 40 camphor globules permanently enclosed therein and maintained in spaced relation to each other, the portions of said tubular textile casing immediately surrounding said globules being of an open texture, while the 45 portions directly intermediate of said globules being of a closer texture, and being constricted.

5. In a device of the character stated, an elongated tubular textile casing, a series of 50 camphor globules permanently enclosed therein and maintained in spaced relation to each other, the portions of said tubular textile casing immediately surrounding said globules being of an open texture, while the 55 portions directly intermediate of said globules being of a closer texture, and being constricted, and a suspension loop at the terminal of said outer tubular textile casing.

6. In a device of the character stated, an 60 elongated tubular braided casing, a series of camphor globules permanently enclosed therein and maintained in spaced relation to each other, the portions of said tubular braided casing immediately surrounding 65 said globules being of an open texture, while the portions directly intermediate of said globules being of a closer texture and being constricted.

CLARENCE LIPPER.
